COMBINED PORTABLE TABLE AND COMPARTMENTED STORAGE UNIT

Edwin Pearlman, Los Angeles County, Calif.
(19720 Ventura Blvd., Woodland Hills, Calif. 91364)

Filed Sept. 28, 1966, Ser. No. 4,068

Term of patent 14 years

(Cl. D33—14)

The right side of the unit, not shown, is a mirror image of the left side.

The dominant features of the design reside in the portions shown in full lines.

I claim:

The ornamental design for a combined portable table and compartmented storage unit, substantially as shown and described.
